UNITED STATES PATENT OFFICE.

STEPHEN C. PORTER, OF BROOKLYN, NEW YORK, ASSIGNOR TO PORTERPHONE CORPORATION, OF NEW YORK, N. Y., A CORPORATION OF NEW YORK.

TELEPHONE-TRANSMITTER.

1,341,997.

Specification of Letters Patent. Patented June 1, 1920.

Application filed April 22, 1918. Serial No. 229,887.

To all whom it may concern:

Be it known that I, STEPHEN C. PORTER, a citizen of the United States, residing at the borough of Brooklyn, city of New York, 5 in the county of Kings and State of New York, have invented certain new and useful Improvements in Telephone-Transmitters, of which the following is a specification.

10 My invention relates to telephone transmitters which are to be used in places where the extraneous noises make the use of the ordinary transmitter impracticable, such as in aeroplanes, hydroplanes, in the presence 15 of gun fire and the like, and it is my object to produce a small, portable transmitter which will operate under the most adverse conditions.

As is well known the pilot and observer 20 in an aeroplane have heretofore been unable to communicate with one another except by signals while in the air by reason of the noise of the engine and propeller and the rush of air through the planes. It is 25 necessary for these two to have the freest communication if the best results are to be obtained, especially in photographic work and in instructing pupils. Heretofore verbal communications had to be made before 30 or after flights and signals depended upon while in the air. Continued use of my invention has shown that the two can freely converse while in the air but at the same time the sound of the engine has not been 35 sufficiently shut out to prevent the pilot's hearing whether or not it is running regularly.

In the drawing, Figure 1 is a sectional view of my improved transmitter; Fig. 2 a 40 face view of the face plate of the case and Fig. 3 a face view of the face plate of the outer cover.

My improved transmitter consists of a microphone having a case 1, diaphragm 2, 45 carbon back 3, carbon grains 4 and opening 5 in the case through which sound reaches the diaphragm. Wires *a* and *b* lead from the case to make the usual connections. The microphone itself forms no part of my 50 invention as any desired type may be used.

To carry out my invention the microphone is tightly packed in sound deadening material 6. In practice this consists in tightly winding the microphone case with strips of woolen felt completely inclosing it

in multiple layers, including the opening 5. In this way the alternate compression and rarefaction of the air due to gun fire is prevented from reaching the diaphragm and it is protected from breakage but all noises 60 originating at a distance are effectually damped before they reach the diaphragm. At the same time sounds originating close to the mouth piece will pass to and affect the diaphragm. 65

The wrapped microphone is then placed in a case 7 the face plate 8 of which, opposite the opening 5 is preferably, but not necessarily, perforated at 9. This face plate may be integral with or separate from 70 the case. These perforations do not come opposite the opening 5 but are placed away from the center as shown in Fig. 2.

In order that the intensity of sound reaching the diaphragm may be controlled 75 the apertures in the face plate 8 are elongated slots and a second plate 8' like the front plate 8 is revolubly secured against the plate 8 and is provided with a handle 18 extending through a slot in the side of 80 the case. By moving this handle 18 the plate 8' is rotated and the apertures in the front plate 8 and the plate 8' may be brought more or less into register thereby controlling the effective size of the sound 85 passages thereby permitting the operator to adjust the transmitter to varying conditions.

A cover 10 with a face plate 11, which may be separate or integral, is perforated at 90 12 and is placed on the outer case 7. The perforations 12 are not opposite the perforations 9 but are centrally grouped as shown in Fig. 3. The face plates 8 and 11 are separated as shown in Fig. 1 forming an air 95 chamber.

A back cap 13 tightly filled with sound insulating material is placed on the back of the case 7.

A flexible, soft rubber mouth piece 15 is 100 then placed on the cover 10 and has the inwardly rolled edge 16 and the inner lip 17, which lip spreads over the edge of the face plate 11, directing the sound waves toward the apertures in the cover plate. The rubber mouth piece is secured to the transmitter by gripping its edge between the outside of the cover 10 and the inside of the back cap 13 as shown in Fig. 1.

In use the rubber mouth piece is firmly 110

held against the mouth and the words are spoken directly into the chamber within the mouth piece. The sound waves pass through the openings 12 and 9, through the 5 sound deadening material 6 and through the microphone opening 5 impinging finally on the diaphragm and vibrating it.

By using sound deadening material around the microphone the effect of extraneous noises is reduced to a minimum and speech is not interfered with. The back 10 cap and its packing prevent sound waves impinging upon the back of the case 7 and protect the microphone from interference 15 on its most exposed side. The air space between the inner lip 17 and the side wall of the soft rubber mouth piece 15 aids in shutting out side sounds.

With my transmitter conversation may be 20 carried on in aeroplanes, under gun fire and under the most disadvantageous extraneous conditions of noise.

I claim:—

1. A telephone transmitter comprising a 25 microphone case provided with an opening, a microphone in said case and a wrapping therefor completely inclosing the same of sound deadening material.

2. A telephone transmitter comprising a 30 microphone case provided with an opening, a microphone in said case, a wrapping therefor completely inclosing the same of sound deadening material and an outer case surrounding the microphone and deadening 35 material.

3. A telephone transmitter comprising a microphone having an opening, a wrapping therefor completely inclosing the same of sound deadening material and an outer case 40 having a face plate provided with perforations opposite to the microphone opening.

4. A telephone transmitter comprising a microphone having an opening, a wrapping therefor completely inclosing the same of 45 sound deadening material, an outer case having a face plate provided with perforations opposite to the microphone opening but not in line therewith.

5. A telephone transmitter comprising a 50 microphone having an opening, a wrapping therefor of sound deadening material, an outer case having a face plate provided with perforations opposite to the microphone opening but not in line therewith and

a cover having a perforated face plate opposite to and spaced from the perforated plate in the outer case. 55

6. A telephone transmitter comprising a microphone having an opening, a wrapping therefor of sound deadening material, an 60 outer case having a face plate provided with perforations opposite to the microphone opening but not in line therewith and a cover having a face plate provided with perforations opposite to and spaced from 65 the face plate of the outer case the perforations of which are not in line with the perforations in said face plate to the outer case.

7. A telephone transmitter comprising a microphone having an opening, a wrapping 70 therefor completely inclosing the same of sound deadening material, an outer case having a perforated face plate opposite to the microphone opening, a protecting cap on the rear of said case and sound insulat- 75 ing material within said case.

8. A telephone transmitter comprising a microphone having an opening, a wrapping of sound deadening material therefor, an outer case having a perforated face plate 80 opposite the microphone opening, a cover having a perforated face plate opposite to and spaced from the face plate of the case and a flexible mouth piece provided with an inner edge extending over that portion 85 of the face plate of the cover adjacent to its edge.

9. A telephone transmitter comprising a microphone having an opening, a wrapping therefor of sound deadening material, an 90 outer case having a perforated face plate opposite to the microphone opening, a back cap on the rear of the outer case, sound insulating material within said cap, a cover having an apertured face plate opposite to 95 and spaced from the face plate of the case and a flexible mouth piece secured to the cover.

10. A telephone transmitter comprising a microphone, a wrapping therefor completely 100 inclosing the same of sound deadening material, an outer case having a perforated face plate opposite to the microphone opening and means for varying the size of said perforations. 105

In testimony whereof I have affixed my signature.

STEPHEN C. PORTER.
